UNITED STATES PATENT OFFICE

134,606

DESIGN FOR A VALVE JACKET

John R. Hiller, San Francisco, Calif.

Application December 22, 1941, Serial No. 104,787

Term of patent 14 years

To all whom it may concern:

Be it known that I, John R. Hiller, a citizen of the United States, residing in the city and county of San Francisco, State of California, have invented a new, original, and ornamental Design for a Valve Jacket, of which the following is a specification, reference being had to the accompanying drawing, forming part thereof.

Fig. 1 is a perspective view of a valve jacket, showing my new design;

Fig. 2 is a top plan view of the same;

Fig. 3 is a side elevational view of the same;
Fig. 4 is an end view looking at one end of the valve jacket, and

Fig. 5 is an end view looking at the opposite end of the valve jacket.

I claim:

The ornamental design for a valve jacket, as shown.

JOHN R. HILLER.
